UNITED STATES PATENT OFFICE.

KENNETH GEORGE ARUNDEL PHILP, OF TORONTO, ONTARIO, CANADA.

AUTOMOBILE SHIPPING DECK.

Application filed December 10, 1925. Serial No. 74,654.

To all whom it may concern:

Be it known that I, KENNETH GEORGE ARUNDEL PHILP, a subject of the King of Great Britain, residing at the city of Toronto, in the county of York, in the Province of Ontario and Dominion of Canada, have invented new and useful Improvements 5 in Automobile Shipping Decks, of which the following is a specification.

10 This invention relates to an automobile shipping deck as described in the present specification and illustrated in the accompanying drawings which form part of the same.

15 The invention consists essentially of the novel features pointed out broadly and specifically in the claims for novelty following a description containing an explanation in detail of an acceptable form of the invention.

20 The decks used at present for shipping automobiles cannot be made to one standard size as they must be varied to suit the varying sizes of box cars; also, many are so constructed that after they have been used once 25 they have to be scrapped, as they are not fit to be used again; and moreover, many are not constructed as to permit of their economical return to the point of shipment since they are large, massive and bulky and 30 are of a rigid construction. It is manifest that since many decks are expensive and cannot be used a second time, the cost of a car delivered to the purchaser must be that much higher, or the equivalent in profit is 35 lost to the dealer.

40 The objects of the invention, therefore, are to construct a deck of such design that it can be made to one size only and be capable of being adapted to any size of box car; to produce a deck that can be used and then returned to the point of shipment in a condition to be used over again, and by providing a substantial construction, it will last a very long time and stand a great deal of 45 abuse and rough handling; to furnish a deck that will realize an appreciable economy to the purchaser or to the seller of an automobile; to manufacture a deck, the construction of which will permit of its folding for 50 purposes of shipping same back to the point of loading; and generally, to supply a strong, practical and economical deck, capable of accomplishing the aforesaid purposes.

55 In the drawings, Figure 1 illustrates the

application of a deck made in accordance with this invention.

Figure 2 is a plan view of the deck.

Figure 3 is a side view.

Figure 4 is a fragmentary view of a 60 typical end of the compression member or of the braces.

Figure 5 is a perspective view of the deck head or bearing block.

Figure 6 is a blank of the plate forming 65 the deck head or bearing block.

Figure 7 is a side view of the compression member.

Figure 8 is a perspective view of the bottom bracket for the compression member. 70

Figure 9 is a perspective view of a typical wall bracket.

Like numerals of reference indicate corresponding parts in the various figures.

In the drawings, 10 are decks supporting the front axle 10^A of the automobile 11, 12 and 13 representing one of the side walls and floor respectively, of a typical box car. As is apparent from the drawings, four 25 decks constitute a complete set, as each one 80 supports one end of the two axles or the hub of a wheel.

The deck consists essentially of the compression member 14 and the two horizontal members or braces 15 and 16, the members being of adjustable length and being pivotally secured to a bearing block or deck head 17 to which all three members converge, and having the other ends secured to the brackets 18, 19 and 20, respectively. 90 It is at once apparent that this deck will adapt itself to various widths of box cars and also to various heights at which the automobile may have to be supported, as well as being adapted to any make of automobile. 95

The compression member 14 is formed of two steel T-shape standard sections 14^A and 14^B, lying back to back, and capable of being secured together in a number of positions by means of bolts 40, and by providing a number of corresponding holes 41 in both of these sections, the member can be adjusted to different lengths. The bottom portion of the section 14^A has the flanges coped off at 21 and the end of the web rounded and punched for a pin pivoting in the bracket 18. The bracket has a number of holes 22 through which lag screws or other suitable fastening means are inserted in securing the brackets 105 110

to the box car wall or floor. The top end of the section 14^B is finished in a like manner to the bottom section 14^A and pivots in the bracket 23 provided on the bearing block 17, and hinge pins or bolts are used for pivotally fastening the compression member to said bracket.

The horizontal members 15 and 16 are constructed in the same manner as the compression member 14, pivoting in the bearing block 17 at one end and in the brackets 19 and 20 at the other. The bearing block is made substantially as shown in Figures 5 and 6, having the plate 24, with flanges 29 integral therewith, and the hinge brackets 23, 25 and 26. The hinge bracket 23 is made of two angles riveted or otherwise secured to the plate 24 and spaced to take the end of the compression member 14, holes 23^A being provided for the hinge pin. The hinge brackets 25 and 26 are constructed of an angle riveted or otherwise fastened to plate 24, and have holes 24^A for the hinge pin. The plate 24 has a hole 28 centrally located, the axis of which is at right angles to the face of the plate, through which the axle or the wheel hub passes. The filler frame is constructed as shown in Figure 6, having flanges 29 upon which the four edges 30 of a filler rest. The filler or bushing, of wood or other suitable material, is applied in the box and made to fit tightly and securely therein, and is provided with a circular hole coinciding with the hole in the box, upon which the axle or wheel hub rests. It is a well known practise that the axles or wheel hubs must be protected from damage while the automobile is being transported. The bracket 18 of the compression member 14 is made as shown in Figure 8, having the lower flanges 30 so that it can be either secured to the wall, as illustrated in Figure 1, or made to rest upon the floor at the wall, or merely made to rest upon the floor.

Corresponding holes 42 are provided in both sections of all strut members to permit of their being made as short as possible for purposes of shipment. As the members are all adjustable to various lengths, if it be found impractical or impossible to secure a bracket in position, as, for instance, if the inside lining of the box car is in part defective, the bracket can be secured to some other part of the box car by changing the length of the member to which the bracket is attached. The drawings show a typical deck constructed in accordance with this invention, using standard T-shapes, but these sections can be replaced by built-up sections of standard angles or by using standard channel beams, or by any reinforced metal construction found suitable.

In the operation or use of this device, the automobile is first placed in its desired position in the box car, one deck head placed

over each end of the axle or wheel hub, the compression member adjusted and fastened in position; the free ends of the braces in each deck are pulled toward one another by a suitable tightening device for wedging or 70 bracing the automobile in position after which the hinge butts are secured to the walls.

After the automobile has been unloaded at the point of delivery, the deck can be 75 returned to the point of shipment to be used over again, by folding all three strut members and suitably tying the ends thereof in their folded relation. The length of the three members are preferably made as short 80 as possible by moving one section upon its corresponding section until the holes coincide and the sections bolted together.

It will be seen that this allows of the practical and economical return of the decks 85 as they are now in a very compact formation.

What I claim is:

1. In an automobile shipping deck, a bearing block forming a support for an axle end 90 or wheel hub of the automobile, and a support and braces of adjustable length hingingly secured to said block for supporting and bracing said block from the wall and floor of the railway car transporting said 95 automobile.

2. In an automobile shipping deck, a bearing block forming a support for an axle end or wheel hub of the automobile, and a support and braces of adjustable length hingingly 100 secured to said block for supporting and bracing said block from the wall of the railway car transporting said automobile.

3. In an automobile shipping deck, a bearing block forming a support for an axle end 105 or wheel hub of the automobile, and a support and braces of adjustable length hingingly secured at one end thereof to said block and brackets hingingly secured to said members at the other end thereof, said brackets 110 being adapted to be fastened to the wall and floor of the railway transporting said automobile.

4. In an automobile shipping deck, a bearing block forming a support for an axle end 115 or wheel hub of the automobile, and a support and braces of adjustable length hingingly secured at one end thereof to said block and brackets hingingly secured to said support and braces at the other end thereof, 120 said brackets being adapted to be fastened to the wall of the railway car transporting said automobile.

5. In an automobile shipping deck, a bearing block forming a support for an axle end 125 or wheel hub of the automobile, a compression member for supporting said block, and braces for securing said block against movement, said member and braces being made up of two sections adapted to be held one 130

upon the other in various positions, and brackets hingingly secured to said member and braces for pivotally securing them to the wall of the railway car transporting said automobile.

6. In an automobile shipping deck, a bearing block forming a support for an axle end or wheel hub of the automobile, a compression member supporting said block, and braces for securing said block against movement, said member and braces being each made up of two sections in slidable engagement and having holes in one section co-acting with corresponding holes in the other section for securing said sections together at varying effective lengths of the member and braces, and brackets hingingly secured to said member and braces for pivotally securing same to the wall of the railway car transporting said automobile.

7. In an automobile shipping deck, a plate forming a frame adapted to enclose a filler supporting an axle end or wheel hub of the automobile, hinge brackets secured to said

plate, a compression member and two braces pivoting at one end in said hinge brackets, and bracket hingingly secured to the other end of said member and braces and adapted to be fastened to the wall of the railway car transporting said automobile.

8. In an automobile shipping deck, a bearing block forming a support for an axle end or wheel hub of the automobile, a compression member supporting said bearing block, and braces for securing said block against movement, said member and braces being made up of two T-sections lying back to back in slidable engagement with means therein adapted to hold said sections in different positions one upon the other, and hinge brackets pivoting in one end of said compression member and braces for securing same to the wall of the railway car transporting said automobile.

Signed at the city of Toronto, Canada, 45
this 21st day of November, 1925.

KENNETH GEORGE ARUNDEL PHILP.
